MACHINE FOR FORMING MATERIAL

George D. Rechton, Los Angeles, Delbert J. Ward, Sherman Oaks, and Jack H. Watson, Los Angeles, Calif., assignors to Douglas Aircraft Company, Inc., Santa Monica, Calif.

Application September 7, 1942, Serial No. 457,630

27 Claims. (Cl. 219—3)

This invention relates to a machine for forming bodies of metal and other materials and particularly to a machine for dimpling or otherwise flexurally forming sheet metal. It also relates to a machine for forming sheets of magnesium alloy and other metals and materials having qualities which prevent their being formed at ordinary temperatures without the development of structural weakness, and particularly to a machine for dimpling, at suitably elevated temperatures, magnesium sheet metal parts for the reception of flush rivets in the manufacture of aircraft, aircraft accessories, or other products.

The word "forming," as herein used, means any processing operation which establishes or changes the shape or dimensions of an article or divides the article into a plurality of articles, such as bending, punching, blanking, stamping and shearing. The invention as to some of its features, is applicable to machines for forming plastic and other non-metallic articles.

The aviation industry, in line with the trend toward lighter and faster aircraft, has been steadily increasing the use of the lighter materials, such as magnesium. Although magnesium ranks in eighth place in abundance among the elements of the earth's crust, it has not been used extensively in industry until the last few years. The slow adoption of this metal for airplane and other construction has been due in a great degree to difficulties in perfecting economical and practical methods of processing the same.

There have been many attempts to cold-form sheets of those magnesium alloys characterized by structural strength, which have usually failed of their purpose. For example, in dimpling sheets of magnesium alloys it has been found that incipient fracture cracks will appear adjacent the sharp radius bend formed at the base of the dimple. These cracks indicate structural weakness which makes the sheet undesirable for use in aircraft construction.

Research and experimental work has shown that by heating the sheets of magnesium alloys to an ascertained temperature, for example in the case of one alloy to approximately 700° Fahrenheit, these metals can be dimpled or otherwise worked without causing fracture. Following out this discovery, several different methods have been employed to heat the sheet metal preparatory to dimpling, each of which has for one reason or another proven unsatisfactory. One of the methods consists of heating the sheet electrically by passing a current therethrough, using the dimpling dies as electrodes

in a manner similar to that followed in a spot-welding machine. This method causes the dimpled metal and the dies to become pitted from excessive arcing which takes place due to the insulating qualities of the surface-protecting pickling coat on the magnesium sheet. This difficulty, coupled with excessive heating and consequent softening and deformation of the dies renders a machine for this method of heating metal sheets impractical, and expensive in operation. In order to avoid these undesirable results this invention contemplates the provision of a machine having a heating means which does not involve excessive heating of the dies and does not involve transmitting currents of electricity through the dies or other electrodes and/or the sheet.

This invention is herein shown embodied in an automatic magnesium sheet dimpling device 20 which heats the sheet and dimples it while in heated condition. Two silver faced electric heating elements or heating bodies are provided on the machine which are placed one above the sheet and one below. These elements when heated are brought into contact with the upper and lower faces of the sheet, securing an even distribution of heat through the sheet adjacent the rivet hole to be dimpled. The dimpling gun is pneumatically operated in accordance with 25 standard practice and the movement of the heating elements into and out of contact with the magnesium sheet is preferably also accomplished by pneumatic means, the selector valves of the pneumatic devices being electrically actuated and their actuation accomplished in a work cycle by 30 a system of electrical relays and other control equipment, the cycle being initiated by a single manually operated switch.

One object of this invention is to provide a 40 dimpling or other forming machine having pneumatically operated dies, in which the pneumatic valves therefor are electrically actuated by a lever under the manual control of the operator.

Another object of the invention is to provide 45 a dimpling or other forming machine which is simple in construction, economical to operate, and completes the cycle of steps of the dimpling operation within a minimum time interval.

Another object of this invention is to provide 50 a machine for dimpling or otherwise forming sheets of magnesium or other metals or materials which develop structural weakness when cold formed or which for other reasons should be formed at a high temperature in which the cycle of operative steps including heating of

the metal sheet is initiated by a single act of the operator and is automatic thereafter, excepting the last step which is manually controlled.

Another object of this invention is to provide a machine of the character described having means for affording a visible indication of its several functions.

Another object of this invention is to provide a machine which, at the will of the operator, may be utilized to dimple or otherwise form either Dural sheets or sheets of magnesium alloy or other metals or materials which are formed to advantage at relatively high temperatures.

Another object of this invention is to provide a machine of the character described having means for heating the metal to be formed without a destructive effect upon the protective pickling coat of the metal and also without destructive heating of the dies for dimpling or otherwise forming the metal sheet.

Another object of this invention is to provide a machine of the character described in which the heating elements are constructed to hold the sheet of metal or other material securely in position during the heating operation.

Another object of this invention is to provide a machine of the character described, in which one of the heating elements is formed to provide a clearance for previously formed dimples, or other raised areas on the sheet.

Another object of this invention is the provision of a machine of the character described in which the heating elements are faced with a metal providing the maximum rate of heat transfer from the heat generating means within the heater to the sheet.

Further objects and advantages of this invention will be brought out in the following description taken in connection with the accompanying drawings and appended claims. In the drawings, which are for illustrative purposes only:

Figure 1 is a side elevation of a dimpling machine embodying this invention.

Figure 2 is a front elevation of the machine shown in Figure 1.

Figure 3 is a schematic view showing the dimpling devices, the pneumatic mechanism for their operation, and a wiring diagram of the electrical equipment for the heating elements, for control of the pneumatic equipment and for performing other functions in the operation of the machine.

Figure 4 is a fragmentary schematic view showing a modified circuit for supplying current to the heating elements.

Figure 5 is an enlarged sectional view of the dimpling dies and heating elements showing the heating elements in their heating position.

Figure 6 is an enlarged sectional view similar to Figure 5 showing the heating elements in retracted position and the dimpling dies in forming position.

Figure 7 is a plan view of one of the heating elements showing the feature of its construction providing for clearing previously dimpled holes.

Figure 8 is a side elevational view of the heating element shown in Figure 7.

Figure 9 is a side elevation of a modified form of heating element designed to concentrate the heat on a limited area of the sheet adjacently surrounding the rivet hole.

Figure 10 is a graph representing the magnesium end of a magnesium aluminum equilibrium phase diagram.

While a dimpling machine has been selected

to disclose this invention, it will be understood that, as to some of its features, the invention is not restricted to a dimpling machine but is applicable to other forming machines.

Figures 1 and 2 show a dimpling machine 10 having a base 12 upon which is mounted a supporting column 14. A pair of generally horizontal laterally extending arms 16 and 18 are clamped to the column 14, the upper arm 18 supporting at its outer end a dimpling gun assembly 20 and the lower arm 16 supporting at its outer end a lower dimpling anvil assembly 22.

The dimpling gun assembly 20 is slideable vertically reciprocated in the guide 19 at the outer end of the upper arm 18 by a lever 26 which is fulcrumed at 27 between ears 24 extending upwardly from the upper arm 18 and which is connected at its outer end to the upper end of the dimpling gun assembly at 34 and is connected at its inner end at 30 to a piston rod 29 of a piston 32 (not shown in Figures 1 and 2) which reciprocates within a pneumatic cylinder 28 mounted upon the rear end of the upper arm 18. The lever 26 is spring loaded by a spring 42 which is seated under a compression between a stationary lug 40 and a collar nut 44 on a bolt 38 which passes through an eye 39 in the lug 40 and is pivoted at its outer end to the free end of a depending arm 36 on the lever 26. A stop bar 31 is mounted on the arm 18 to engage the under side of the rear end of the lever 26 to prevent the piston of the piston rod 29 from striking the bottom of the cylinder 28.

The lower end of the dimpling gun assembly 20, including the female die 59 thereof, is surrounded by a heating element or heating body 52 having an aperture 58. The heating element 52 is held in position laterally with respect to the dimpling gun assembly and supported vertically by a piston 50 which is vertically reciprocably movable within a pneumatic cylinder 48 mounted upon the outer end of the upper arm 18 adjacent the inner side of the dimpling gun assembly. Admission of air to the pneumatic cylinder 48 moves the heating element downwardly and upon exhaust of air from this cylinder, the heating element is retracted to its normal position by the action of a tension spring 56 secured at its upper and lower ends to the guide 19 and piston 50 respectively. A cable 56 contains the electrical conductors for heating the element 52 and registering its temperature.

To the upper face of the outer end of the arm 16 is secured a pneumatic cylinder 60 to which air is supplied at an inlet 62 in which reciprocates a tubular piston 64 (see Figure 5), the piston 64 carrying at its upper end a heating element or heating body 66 which is apertured for the accommodation of a stationary male dimpling die 70. The support for the die 70 extends downwardly through the hollow piston 64 and is mounted upon the lower arm 16. The heating element 66 is thus vertically slideable with respect to the stationary dimpling die 70 from a lower retracted position to an upper position in which it makes contact with the metal sheet to be dimpled. A cable 68 contains the conductor wires for supplying the energy to heat the heating element 66 and to register its temperature. A micro switch 72, closed by depression of a button 74 upon downward movement of the heater 66 to its lower retracted position, is connected to the control mechanism by the conductors within a cable 73, the cables 68 and 73 entering a junction box 75 from which electrical connections are

made to the control and indicating devices by the conductors in a cable 77.

The system of air conduits and pneumatic control devices for operation of the pneumatic cylinders 28, 48 and 60, and for operation of the dimpling gun 20, are shown schematically in Figure 3, some of the conduits and control devices appearing in the structural views, Figures 1 and 2. Air enters the machine under pressure at 100 through a gate valve 102 and may proceed to an electrically controlled valve 104 through the pipe 103 and thence, when valve 104 is opened, through a pipe 132 not seen in Figures 1 and 2 but shown in Figure 3 to cylinder 28 to depress the dimpling gun assembly 20.

Air may also pass from the gate valve 102 to the electrically controlled valve 106 through pipe 105, for transmission when valve 106 is in open position through pipes 118 and 122 to cylinders 48 and 60 for movement of the heating elements 52 and 66 respectively from their retracted position as shown in Figure 1 to their position of contact with the metal sheet to be dimpled as shown in Figure 5. Electrically controlled exhaust valves 110 and 112 are in closed position when valves 104 and 106 respectively are in open position, and vice versa. They function to relieve the air pressure in cylinder 28 and in cylinders 48 and 60 respectively for the elevation of the dimpling gun in the case of cylinder 28 and the retraction of the heating elements 52 and 66 in the case of the cylinders 48 and 60.

A valve 121 in the pipe 118 and a pressure gage 123 provide means for regulating the air pressure transmitted to cylinders 48 and 60 at any desired value, thus regulating the degree of pressure at which the heating elements engage the metal sheet. The section of exhaust pipe in which exhaust valve 110 is placed, the air supply pipe 103 and the pipe 132 leading to the cylinder 28 are connected as shown by a T 130. The exhaust pipe in which valve 112 is placed, the air supply pipe 105 and the pipe 118 leading to the cylinders 48 and 60 are connected as shown by means of a T 116 while pipe 118 is connected to pipe 122 by the T 117.

To T 136 interposed in the air supply pipe 103 is connected a pipe 138 leading to a pressure regulating valve 140, which in conjunction with a pressure gage 142 serves to regulate the air pressure in pipe 144 leading to the dimpling gun assembly 20 and tripping the pneumatic firing device for applying an impulse force to the dimpling die of the dimpling gun assembly when the pressure between the upper and lower dimpling dies reaches a prescribed value after the dimpling gun assembly has been lowered and the two dies brought into engagement with the metal sheet to be dimpled, through depression of the gun due to actuation of the piston 32 operating in cylinder 28.

Upon an angle support 16 secured to the upper arm 18 is mounted a control box 78 which houses the electrical control equipment for the supply of current to the heaters 52 and 66 for sequential control of the electrical devices for the actuation of valves 104, 110, 106, and 112. These devices and their connections are enclosed within dash lines on Figure 3 and designated by the numeral 78. The valves 104, 110, 106 and 112 are electrically actuated by solenoids in a manner to be hereinafter explained, the conductors from the control box 78 to the various valve operating solenoids passing through a connection 78

box 108 mounted on the inner end of the upper arm 18.

The front face of the control box 78 serves as a control panel 79 upon which are mounted the several dial switches and other manual controls, and the value registering instruments for use in operating the machine. These several control devices and registering instruments will be referred to and described in the course of the following explanation of the wiring diagram of Figure 3. On this diagram the arrows indicate the direction of potential drop.

Electrical energy is supplied to the control box by a lead-in cable 80 comprising conductors 146 and 147. A warning light 82, connected across these main conductors 146 and 147, is placed on the panel to indicate passage of current to the control devices of the control box and thence to the heating elements and electrically operated air valves. A line switch 83 controls the supply of current to the machine. Conductors 152 and 154 constitute a shunt heating circuit connected to the wires 146 and 147 of the power circuit, and supply electrical energy through a transformer 158 to the heating elements 52 and 66 in parallel through wires 162 and 164. The transformer 158 is of the variable tap type and includes an adjusting knob 88 for controlling the wattage input and temperature of the heaters. The primary of the transformer 158 is connected to the conductors 152 and 154 by a normally open switch 156. This switch is automatically closed upon closing of the main switch 83 by a relay coil 149 which is connected between power lines 146 and 147 by conductor 151 and conductor 154.

The pressure valve 106 and exhaust valve 112 are operated by solenoids 194 and 196 respectively, each valve being spring retracted to closed position upon the de-energization of the associated solenoid. Solenoid 194 is connected to power line 147 by a shunt circuit comprising the conductors 171, 173, switch 299, conductors 175 and 167, and to line 146 by a conductor 169. Exhaust solenoid 196 is connected to the power line 146 by a conductor 169 and to line 147 by a shunt circuit comprising conductors 177, 179, switch 209, and conductors 175 and 167.

The pressure valve 104 and the discharge valve 110 for operation of the piston 32 in cylinder 28 are actuated by solenoids 190 and 192 respectively, each valve being spring retracted to its closed position. Inlet solenoid 190 is connected to the power line 146 by the conductor 81 and to power line 147 by a shunt circuit comprising the conductor 183 including the micro switch 72, conductor 185, switch 192, conductor 187, selector switch 198 and conductor 167. Solenoid 192 is connected to the power line 146 by the conductor 181 and to line 147 by a shunt circuit comprising conductors 189, 191, switch 217, conductor 187, selector switch 198 and conductor 167.

A control circuit which is connected to the power lines 146 and 147 comprises the conductor 165, the switch 96 operated by the foot pedal 98, as best seen in Figures 1 and 2, and conductor 167 in which is disposed relay coil 186.

Another control circuit which is also closed by the foot pedal switch 96 and is arranged in parallel with the control relay circuit of the relay 186 comprises conductors 165, 167 and 193, anode 172, and cathode 197 of a rectifier tube 170, conductor 195, conductor 202 in which is disposed relay coil 188, anode 180 and cathode 182 of a gas trigger tube 184, conductors 241 and 167. The filament 174 of the rectifier tube 170 is connected

to the power lines 146 and 147 by conductors 153, 151, and 167. The effect of the rectifier tube is to impress a direct current potential upon the control relay coil 188 and the anode of the trigger tube 184.

Current flow from anode 180 to cathode 182 of the gas trigger tube 184 occurs upon charging of the grid 201 to a predetermined value, the resistor 201' limiting current flow from the grid 201 to cathode 182. The grid is charged with a potential voltage to the prescribed value by an RC voltage accumulator circuit 199 connected between the cathode 197 of the rectifier tube 170 and the conductor 167. This circuit includes a filtering circuit 200 for filtering the same and the relay circuit. As usual this accumulator circuit comprises resistance and condenser elements as shown, the time interval required for voltage build-up being regulated by the variable resistor 176.

Discharge of the RC circuit is provided for by a discharge circuit comprising the conductor 203 in which is interposed the usual resistance element 205.

When the switch 96 is closed the relay 186 is energized which operates the gage switch 145 to move switch arm 209 into engagement with contact 207, connecting conductors 173 and 175 to complete the circuit by which a solenoid 194 is energized for the operation of the valve 106.

The movement of switch arm 209 out of engagement with the contact 213 also opens the discharge circuit, and the accumulator circuit begins to charge. When the accumulator circuit is charged with the predetermined voltage the grid 201 actuates the trigger tube 184, allowing current to flow from the anode 180 to cathode 182 and the relay coil 188 is energized.

Energization of the relay 188 opens the switch 221 in the conductor 167 de-energizing relay coil 183. De-energization of the relay coil 186 causes the switch arm 209 to be moved into engagement with the contact 211 to electrically connect conductor 179 with 175 to complete the circuit for energization of solenoid 196 for the operation of the exhaust valve 112. Energization of the relay coil 188 also causes switch arm 217 to engage the contact 215 to electrically connect conductor 185 with the conductor 187 and thus energize the solenoid 190 which opens the pressure valve 104 for the lowering of the dimpling assembly 20. When the switch 96 is opened the relay 188 is de-energized and the switch 221 is closed. The de-energization of the relay 188 also causes the switch arm 217 to be moved into engagement with contact 219 to connect conductor 191 with conductor 187 and completes the circuit for energization of the solenoid 192 for opening the discharge valve 110 resulting in the elevation of the dimpling gun assembly 20.

The micro switch 72 is in closed position when the heater element 66 is in its lower-most position and opens at the initiation of the upward movement of this heater in response to opening of the valve 110. The micro switch 72 is interposed in the conductor 183 and prevents operation of the solenoid 190 in response to closing of the switch 215, 217 until the heater 66 has reached the lower limit of its travel.

A stop gun gang switch lever, which is shown on the panel 79 at 245 operates a normally closed switch 265 interposed in conductor 181 and a normally closed switch 267 which normally shorts-circuits a high resistance element 223 of the voltage accumulator circuit 199. The lever 245 in one

position closes the switches 265 and 267 for normal operation of the machine. When the lever 245 is thrown to its other position, switches 265 and 267 are opened, having the effect of preventing movement of the dimpling gun assembly 20 and increasing the time interval required to charge the grid 201 sufficiently for passage of current from anode 180 to cathode 182 of the gas trigger tube 184.

10 The machine is also designed for dimpling "dural" or other metals which may be worked cold without the development of structural weakness. A thumb knob mounted on the panel 79, and indicated in Figure 2 by the numeral 92, 15 operates four switches which appear on the wiring diagram of Figure 3 and are designated by the numerals 269, 198, 271 and 272. Switch 269 is interposed in conductor 151 and when open prevents energization of the relay coil 149 which 20 controls the heater circuit. Switch 198 has two positions, designated on the diagram as M and D. When this switch is in position M conductor 187 is connected to conductor 167 permitting operation of the pressure valve 106 and discharge valve 112. When it is in position D it short-circuits the voltage accumulator discharge circuit 199, connecting this circuit through conductor 229 to conductor 167.

25 Switch 271 has two positions, indicated by the letters M and D. When in the position M conductors 171 and 173 are connected completing the circuit for operation of the valve 106. When in position D conductor 183 is connected to conductor 173 through a cross-circuit conductor 225 for energization of solenoid 190 for the operation of pressure valve 104 lowering the dimpling gun assembly.

30 Switch 272 has two positions, designated by the letters M and D. When this switch is in position M conductor 177 is connected to conductor 179, completing the circuit to solenoid 196 for the operation of discharge valve 112 to retract the heating elements to their normal positions. When this switch is in position D it connects conductor 189 with conductor 179 through the cross circuit conductor 227, completing a circuit for the operation of solenoid 192, which actuates discharge valve 110 for the elevation of the dimpling gun assembly.

35 When the thumb knob 92 is turned to the left-hand position, as shown in Figure 2 and designated "Dow," switch 269 is closed and switches 198, 271, and 272 are in their M position. When the knob 92 is in the right-hand position, designated "Dural," switch 269 is open and the other three switches are in their D position.

40 The heating elements 52 and 66 and the dimpling dies 59 and 70, are shown in Figures 5 and 6. The heating element 52, as above described, is circularly apertured for encirclement of the upper die 59, and consists of a shell 204, a layer 206 of heat insulating material, heating conductors 249 in an electrical insulating sheath 251, and a facing 214 of preferably pure silver or of copper with a heavy plating of pure silver on its lower heating face. The lower heating element 66 similarly comprises a shell 216 secured to the upper end of the piston 64, a layer of heat insulation 218, heating conductor 253 in an insulating sheathing 255 and a facing 220 of pure silver or of copper with a heavy plating of pure silver on its heating face. The silver has the combination of high specific heat, high conductivity and non-oxidizing qualities, which make it

one of the few materials, if not the only material, which is practical as a contact facing.

The piston 64, as has been above described, is tubular and slides vertically upon a tool support 257 which carries the lower male die 70. When a magnesium sheet 208 is placed in the machine for the dimpling operation, one of the previously drilled rivet holes therein is placed upon a pilot 222 of the die 70, the sheet being supported by the conical connection 261 between the pilot 222 and the body of the die 70.

The heating elements are designed to have different temperatures, the lower heating element 66 being maintained for example at a temperature preferably of about 650° and the upper heater being maintained at a temperature of preferably 900° for dimpling the hard rolled magnesium alloy known as Dow metal J, the composition of which is 92.5% magnesium, 6.5% aluminum and a remainder of zinc and manganese. The lower heating element in its normal retracted position is spaced relatively close to the sheet of magnesium metal and the upper heater 52 is spaced relatively distant therefrom. The heating face of the lower element 66 is also preferably greater in area than the heating face of the upper heating element 52. The capacity of each heater is sufficient to maintain its heating surface at its prescribed temperature.

As a result of these relative heating capacities, heating surface areas, and spacings from the metal sheet, the two heating elements, while held in their retracted position, will, by radiation and to some extent by convection of air currents, heat the metal sheet, although to a degree substantially less than 650°, the upper heating element contributing to a substantially lesser extent to this heating action.

As the heating elements are moved into and out of contact with the sheet to successively dimple a row of rivet holes, the temperature of the area surrounding any given rivet hole will rise as the operator moves it toward the dimpling dies, reaching a temperature of 650°, or nearly that temperature, when it is between the dimpling dies.

When at this juncture the heating elements are moved into contact with the metal sheet, the upper heating element acts to bring the temperature of the metal sheet rapidly to the optimum working temperature of approximately 650° in a relatively few seconds. In the operation of the machine, after a metal sheet is initially heated prior to the first dimpling operation thereon, it requires as little as two seconds of contact of the heating elements with the sheet for bringing that portion of it surrounding a rivet hole to proper working temperature. The upper heater will not overheat the metal in this brief time interval, since the lower heater, being at 650° and of larger size and having a silver facing, will absorb heat from the upper heater and inhibit a rise in the temperature of the metal sheet.

After the temperature of the heating elements has been regulated to those values suitable for heating a given material to forming temperature, the variable resistor 176 is adjusted to provide a time interval of contact of the heating elements with the sheet which will give the sheet optimum temperature for the desired forming operation.

It is important that the sheet be brought accurately to this temperature. If, for instance, the operation is that of dimpling and the adjustment provides too high a temperature, the dim-

ples will be indented too deeply and the sheet will warp. If the temperature is too low, the sheet will develop cracks around the dimple.

A thermocouple (not shown) is embedded in the silver facing of each heating element. Referring to the wiring diagram of Figure 3, the thermocouple of the upper heating element is connected by conductors 161 and 163 to the terminals on one side of a double-throw switch 86. The thermocouple of the lower heater is connected by conductors 157 and 159 to the terminals on the other side of this switch. The movable arms of this switch are connected by conductors 274 and 275 to an electric temperature meter 84. The movable arms of the switch 86 are held by a spring normally in engagement with the terminals of the conductors 157 and 159, since it is more important that the operator have indicated the temperature of the lower heater. This is true because, as has been explained above, this heater is normally maintained at a temperature less than the upper heater and as it absorbs heat from the sheet the temperature thereof will more closely approximate the temperature of the sheet. When the operator desires to check the temperature of the upper heater he may do so by throwing the switch 86 to connect conductors 161 and 163 with conductors 274 and 275 leading to the meter.

In Figure 3, there is shown a conductor 233 leading off from conductor 156 between the variable tap of the transformer 158 and switch 156. This may be connected as shown in Figure 4 to one of the heaters, preferably the lower heater, this connection and the conductor 160 connecting the transformer coils, establishing a circuit for the lower heater which bypasses the transformer coils, so that manipulation of the transformer 158 by the operator will regulate the temperature of one heater only, which preferably is the upper heater.

The heating elements 52 and 66 are so constructed and secured in place that they are readily removable, the flexible cable leading thereto being provided, as shown in Figure 1, for that purpose with jacks at 226 and 228. This feature of construction of the machine is of advantage in that it makes it possible to change the heating elements using for metal sheets of different thickness and of different curvature, heating elements of corresponding character.

As shown in Figures 7 and 8, the heating face of the upper heating element is formed with slots 230 for clearing previously formed dimples after the metal sheet is moved laterally of the heating elements.

In Figure 9, the contact face 278 of a heating element 52' is substantially smaller in area than the heating chamber 279 whereby heat may be applied to the metal sheet in a concentrated manner.

The panel 78 at the end of the control box 76, as shown in Figure 2, mounts the switch 86 for selectively connecting the thermocouples of the heaters with the temperature meter 84, which is also mounted upon the panel 79. The lamp 82 is mounted on the panel 78, which also carries the manipulating knob 88 of the transformer 158, the handle of the line switch 83, the handles of the stop gun gang switch 245 and the Dow-Dural gang switch 92 and manipulating knob 90 of the variable resistor 176.

In the operation of the machine for dimpling magnesium alloy, the knob 92 is turned to the

"Dow" position and the line switch 83 is closed. Closing of the line switch 83 lights the beacon lamp 32, energizes the heating circuit relay 149, closing switch 156 to pass current through the heaters 52 and 66. The temperature of the heaters is regulated by adjustment of the transformer 153, accomplished by manipulating the transformer manipulating knob 88. Since the two heaters are connected in parallel, the temperature of the heaters are proportionately raised or lowered together. However, if the heaters are connected, as shown in Figure 4, the temperature of the one heater may be regulated without affecting the temperature of the other heater.

A sheet of magnesium alloy is now placed in the machine with one of the rivet holes therein placed upon the pilot 222 of the lower die 70, radiation from the lower heating element, and to a lesser extent from the upper heating element, causing a substantial elevation of the temperature of the metal sheet. Closing of the line switch 83 also sends current through filament 174 of the rectifier tube 170. If, as is usually the case, it is desired to preheat the metal before dimpling the first rivet hole in the sheet, stop gun gang switch 245 is temporarily thrown at this time, opening switches 265 and 267.

Upon depression of the foot lever 98, current flows to the control relay 186 which connects the circuit leading to the pressure valve 106 and opens the switch in conductor 203. Current now flows through conductor 169 to the solenoid 194, actuating pressure valve 106 operating the piston in cylinder 48 and the piston in cylinder 60 to bring the heating elements in contact with the metal sheet. While the heating elements are held against the metal sheet by valve 106, voltage is being built up in voltage accumulator circuit 200, and at the end of a time interval, which may be regulated for example at two seconds by adjustment of the knob 90, the gas trigger tube 184 is conditioned for passage of direct current from the rectifier tube 170 through the direct current control relay coil 188. When this coil 188 is energized switch 221 is opened de-energizing coil 186, switch arm 217 engages contact 215 connecting conductors 185 and 187, and disconnecting conductors 191 and 187. De-energization of relay coil 186 connects conductors 179 and 175 to energize solenoid 196, actuating discharge valve 112 to withdraw the heating elements to their retracted position.

De-energization of coil 186 also closes switch 213, permitting discharge of the RC circuit 200 through the resistance 205 resetting this circuit for the next energization of relay coil 188. The gas trigger tube 184, as is evident from the above, allows energization of relay coil 186 to hold the heating elements in contact with the metal sheet for a prescribed time interval which is unaffected reactively by the movements of the pneumatically energized devices or the flow of current through the solenoids which operate these valves. This electronic control of the heating time interval has a definite advantage over a mechanical, pneumatic or other type of time control. It is highly accurate and is unaffected by the vibration or jars which unavoidably attend the operation of the machine.

When the lower heating element closes the microswitch 72, and assuming that the stop gun gang switch lever 245 has been opened, the circuit which energizes solenoid 190 is completed except for the switch 265 which is held open by the gang switch. Since this gang switch also

is holding switch 267 open, the time interval for conditioning the gas trigger tube 184 for passage of current from its anode 180 to its cathode 182 for the energization of control relay coil 188 is lengthened by several seconds, for example 5 seconds. Therefore, as long as the stop gun gang switch holds switch 265 and switch 267 in open position, the dimpling gun assembly will not operate and the heating phase of the operative cycle will be lengthened.

When the sheet is brought close to dimpling temperature, the lever 245 is moved to close switches 265 and 267, shortening the time interval of contact of the heating elements with the metal sheet and closing the circuit to the dimpling gun solenoids 190 and 192. When the control relay coil 188 is energized by operation of the gas trigger tube 184, the lower heating element 66 will depress the button 74 closing the microswitch 72 completing the circuit to solenoid 190 for the actuation of pressure valve 104 to lower the dimpling gun assembly. When the dimpling gun assembly comes into contact with the metal sheet, if it is of the one-shot type, it will deliver its percussion blow to the upper dimpling die upon development of the prescribed pressure against the metal sheet and it is of the rattle type it will deliver a succession of blows in the manner characteristic of percussion tools of this kind.

The operator now lifts his foot from the foot lever 98, opening switch 96 which breaks the circuit to relay 188. De-energization of relay 188 closes the circuit to solenoid 192 which then actuates the relief valve 110 causing the spring 42 to elevate the dimpling gun assembly to its retracted position. De-energization of relay 188 also, as described above, closes switch 221 which resets the circuit to relay 186 for its energization, when the operator shall again close foot pedal switch 96. In using the machine the operator releases the foot pressure on the pedal 98 to raise the dimpling gun at the completion of each dimpling operation and again depresses pedal 98 after he has moved the metal sheet to bring the next rivet hole into position for the next dimpling operation, whereupon the cycle is repeated.

When the machine is used for dimpling sheets of dural metal, which do not have to be heated, the knob 92 is turned to its right-hand position, opening switch 269 and placing switches 198 and 271 and 272 in their D positions. Opening of the switch 269 de-energizes relay 149, opening the switch 156 and disconnecting the heaters. Movement of the switch 198 to the D position short-circuits the voltage accumulator circuit 200 preventing charging of the grid 201 of the gas trigger tube 184, thus rendering inoperative the control relay coil 188. When the foot pedal switch 96 is now closed, current flows through the relay coil 186 connecting the switch arm 209 with contact 207 and when the foot pedal switch 96 is raised the relay coil 186 is de-energized bringing the switch arm 209 into engagement with the contact 211. When the switch arm 209 engages contact 207 a circuit is completed through conductor 181, solenoid 190, conductor 183 including micro switch 72 (now held closed by the heater 66) conductor 225, switch 271, conductor 173 and conductor 175, actuating valve 104 to lower the dimpling gun assembly 20. De-energization of the relay 186 causes switch arm 209 to engage contact 211 which completes a circuit comprising conductors 181, solenoid 192, conductor 189, conductor 227, switch 272, conductor

179 and conductor 175, closing solenoid 192 to actuate solenoid 110 to raise the dimpling gun assembly 20.

The fluid pressure for the operation of the dimpling gun assembly should be closely regulated by valve 140 in correlation with the regulation of the temperature of the heating elements. Excessive pressure at a given temperature of the metal sheet may cause thinning of the dimpled and adjacent areas or other deformation of the sheet. Insufficient pressure at a given temperature may result in incompletely formed dimples. This relationship of pressure and temperature may have the following theoretical explanation:

Certain metals and particularly alloys in which magnesium is the matrix and aluminum is the principal alloyed metal, have several physical states, characterized by different molecular relationships, which have a controlling influence on their forming performance. For instance, as taken from the graph shown in Figure 10 of the drawings in which ordinates are degrees of temperature and abscissae are percentages of aluminum in an alloy of magnesium and aluminum, in which A represents the liquidus line, B the solidus line and C the critical slippage line, a magnesium alloy of 5% aluminum cannot be formed without molecular changes of a weakening character at any temperature below point c on the critical slippage line. Between points c and b, it can be formed at relatively heavy pressures. For, when between these temperatures b and c, the metal is in the solidus state, and while yet crystalline, its crystalline structure will yield without fracture along both pyramidal and basal planes.

Between points a and b the metal is partly solidus and partly liquidus and the forming pressures required are lighter. At temperatures above point a, the alloy is wholly without crystalline structure and may be formed with very light pressures. If the temperature is much above point a, the mechanical properties of the alloy may be undesirably affected and there is another disadvantage in that even the lightest pressures will then thin the metal or cause it to flow. These high temperatures should therefore not ordinarily be used.

By flow is meant that internal relative movement of component bodies of the material which is a familiar distinguishing characteristic quality of liquids. If a component body in the forming operation maintains its same proximate relation to surrounding bodies, merely changing its shape and orientation, as by means of slip plane movement, such a movement is not "flow." If a component body moves into new relationships with new surrounding bodies, the material is said to "flow" as the word is herein used. In flexural forming if the conditions are such, as for instance a combination of excessive temperature and stresses, as to cause localized projections, such as wrinkles, at the edges of the forming faces of the dies, the movement of the material to form these projections is a flow movement.

Since many flexural forming operations, such as sheet dimpling, are localized on the sheet, the heating of the sheet preparatory to the forming operation is for practical reasons also localized in character. It has been found in the case of certain materials such as Dow metal J, above referred to, that with localized heating to temperatures above point a, warping of the sheet, especially of a large thin sheet, occurs, rendering the finished article unusable for some purposes,

as in airfoil surfaces. To overcome this warping, it has been found that by heating the sheet to a temperature somewhere between a and c, and by using a heavier forming pressure, warping is eliminated and perfect forming is at the same time secured. The pressure must not, however, be sufficient to appreciably flatten the sheet or cause it to appreciably flow. Insufficient pressure, depending on the temperature, will result in an incompletely formed product. In any event the temperature of the sheet must not be below point c on the critical slippage line or fracture will result. The critical slippage point is that temperature below which these metals will not yield under pressure along both pyramidal and basal planes without fracture.

Forming the metal sheet at a lower temperature and at a correspondingly higher pressure has an additional advantage for certain job requirements.

20 Higher forming pressures of a percussive character have a work hardening effect on the metal. Where this work hardening is an advantage in the finished product, it may be accomplished with metals, such as the magnesium alloys herein described, by adjusting the percussive pressure of the dimpling gun or other forming tool to a value which is sufficient to work harden the formed zone and heating the metal to a corresponding temperature between points a and c.

25 While the value of the fluid pressure causing movement of the heating elements into contact with the metal sheet may vary substantially without disadvantage, it should not be so great as to injure the metal sheet nor so small that the heating faces of the elements will not contact the metal sheet with sufficient firmness to provide free conduction of heat from the heating element to the metal.

30 It will be understood that, if desired, the temperature of the heating elements can be thermostatically controlled by the addition of suitable automatic regulatory devices for this purpose, such as are well-known in the electric heating art.

35 45 While there have been described herein certain embodiments of this invention, the invention is not to be understood as confined to these particular embodiments, but is to be given the definition and scope expressed in the following claims.

50 55 If desired, the machine may be adjusted to hold the heating elements stationary in their retracted position and the heat within the dies which is received from the encircling heating elements relied upon to raise the metal sheet to proper forming temperature at the time the dies contact the sheet when brought into forming position. To successfully carry out this method the heating elements must be maintained at a higher temperature for any given forming pressure than their temperature when used in the contact method above described and also the dies must be made of a material which will not lose hardness or other qualities desirable in die forming work, at the temperature required to thus bring the metal sheet to forming temperature. Preferably the material of the die should be relatively non-oxidizable at such a temperature and of high specific heat and high thermal conductivity.

60 65 The expression "heating element" or "heating body" as used herein is not to be limited to an electrically heated element or body, except where modifying or amplifying context implies such a limitation. The expression defines a body or member which has or is associated with heat delivering means whereby its temperature may be

raised, whether that means be an electric current conductor, a heated fluid like steam, or other means.

Specific temperature values mentioned herein are uniformly on the Fahrenheit scale.

We claim:

1. In a machine for forming plates and other objects of metals and other materials at relatively high and critical forming temperatures, including means for forming the plates and other objects while at said temperatures, the combination of: means for holding the plate; a first heating body independent of the forming element of the machine and arranged on one side of the held plate; a second body independent of the forming element of the machine and arranged on the opposite side of the held plate; means for maintaining the first body at a substantially constant normal temperature of a first degree which is not greater than the desired forming temperature of the work article; means for maintaining the second body at a substantially constant normal temperature of a second and substantially greater degree which is greater than the desired forming temperature of the work article; means for initially relatively disposing the heating bodies and plate for radiantly heating the plate by said heating bodies; and means for thereafter relatively disposing the heating bodies and plate for conductively heating the plate by said heating bodies preparatory to the forming operation.

2. In a machine for forming plates and other objects of metals and other materials at relatively high and critical forming temperatures, including means for forming the plates and other objects while at said temperatures, the combination of: means for holding the plate; a first heating body independent of the forming element of the machine and arranged on one side of the held plate and normally held in spaced relation therewith; a second heating body independent of the forming element of the machine and arranged on the opposite side of the held plate and normally held in spaced relation therewith; means for maintaining the first body at a substantially constant normal temperature of a first degree which is not greater than the desired forming temperature of the work article; means for maintaining the second body at a substantially constant normal temperature of a second degree substantially greater than said first degree which is greater than the desired forming temperature of the work article; and means for sequentially, first simultaneously moving said heating bodies into contact with the two sides of the plate respectively, then after a brief time interval retracting said heating bodies to their normal position preparatory to the forming operation.

3. The combination defined in claim 2, and in addition thereto; means for adjusting the normal temperature of one of said heating bodies independently of the normal temperature of the other heating body.

4. The combination defined in claim 2, in which said heating bodies are electrically heated and connected to a current source in parallel, and in addition thereto; means for adjusting the wattage input to said heaters.

5. The combination defined in claim 2 in which said first heating body is normally positioned relatively close to said metal plate for heating said plate to a temperature approximating but substantially less than that of said first heating body when in said normal position and said second heating body is normally positioned relatively

distant from said metal plate and sufficiently spaced therefrom to prevent heating of said plate to a temperature in excess of that of said first heating body.

6. The combination defined in claim 2 in which said first heating body is of relatively large capacity and the area of the heating surface thereof juxtaposed to said metal plate is relatively large and said second heating body is of relatively small capacity and the area of the heating surface thereof juxtaposed to said metal plate is relatively small.

7. The combination defined in claim 2 and in addition thereto, means for regulating said first heating body whereby its constant normal temperature is approximately the optimum forming temperature of the metal of said plate, said first and second heating bodies being of respective heating capacities, sizes of heating faces and normal spaced disposition with reference to said plate such as to inherently heat the plate, when said first heating body is at said optimum forming temperature and said second heating body is at a substantially greater temperature and when said bodies are in normal position, to a temperature less than the temperature of said first heating body.

8. In a machine for forming plates and other articles of metals and other materials at relatively high and critical forming temperatures, including means for forming the plates and other objects while at said temperatures, the combination of: means for holding the plate; and a heating body of extended surface area and independent of the forming element of the machine for flat contact with said held plate at a portion thereof to be formed and for conductive heating of said portion prior to the forming operation thereupon, said heating body including a contact facing of substantially pure silver and having a mass sufficient to give it a thermal capacity many times greater than that of the contacted portion of the work article.

9. In a machine for forming plates and other articles of metals and other materials at relatively high and critical forming temperatures, including means for forming the plates and other objects while at said temperatures, the combination of: means for holding the plate; and a heated body of extended surface area and independent of the forming element of the machine for flat contact with said held plate at a portion thereof to be formed and for conductive heating of said portion prior to the forming operation thereupon, said heating body including a contact member of copper plated with substantially pure silver on the contact face thereof and having a mass sufficient to give it a thermal capacity many times greater than that of the contacted portion of the work article.

10. In a machine for forming plates and other articles of metals and other materials at relatively high temperatures, the combination of: means for holding the plate; a first centrally apertured heating body arranged on one side of the held plate and normally held in spaced relation therewith; a second heating body arranged on the other side of the held plate, said second body being centrally apertured in alignment with the aperture of said first heating body and normally held in spaced relation with said plate; a pair of co-operating forming elements on opposite sides of said plate for forming engagement with said plate and relatively reciprocably movable

along a line toward and away from said plate and coaxial with said apertures the areas of said engagement being centered on the axis of said apertures; and means for sequentially, first simultaneously moving said bodies into contact with the two sides of said plate respectively, then after a brief time interval retracting said heating bodies to their normal positions and immediately thereafter moving said forming elements into and out of operative forming engagement with the plate each forming element being movable relative to its corresponding heater within the aperture thereof.

11. The combination defined in claim 10, in which said forming elements produce in succession a plurality of areas displaced from the plane of the plates, and the spacing of the formed areas is such as to position an earlier formed area opposite at least one of the heating bodies while the next formed area is being formed, and in which at least one of said heating bodies is grooved on its contact face to receive said earlier formed area as the plate is moved laterally between said heating bodies into position for forming the next formed area.

12. The combination defined in claim 10 in which said forming elements are a lower male stationary dimpling die and an upper female vertically reciprocating dimpling die for use with a plate apertured for the reception of the shanks of fasteners and said plate holding means comprises the male die as a centering and levelling supporting means.

13. In a machine for forming plates and other articles of metals and other materials at relatively high and critical forming temperatures, including means for forming the plates and other objects while at said temperatures, the combination of: means for holding the plates; a first heating body of extended surface area for flat contact with the face of said plate and conductive heating thereof, said heating body including a contact member of high specific heat and high thermal conductivity; a second heating body of extended surface area for contact with the other face of said plate and for conductive heating thereof, said heating body including a contact member of high specific heat and high thermal conductivity, said heating bodies being normally disposed out of contact with and spaced from said plate, one of said heating bodies being normally disposed nearer the plate and by reason thereof and by reason of its properties having a greater heating effect on the plate than the other heating body; an electric temperature meter; and a switch for selectively electrically connecting said heating bodies to said meter, said switch being normally resiliently held in position to connect said one heating body to said meter.

14. In a machine for forming plates or other articles of metals or other materials at relatively high and critical forming temperatures, the combination of: a pair of dies for simultaneously engaging from opposite sides and forming a plate held between them; a pair of heaters on opposite sides of and normally spaced from the plate in a retracted radiantly heating position, said heaters being arranged adjacent the axis of said dies; a first fluid pressure operated means for moving said heaters from said retracted position into contactual heating position with relation to the plate; means for moving said heaters from said heating position to said retracted position; means including a second fluid pressure operated means for relatively moving said dies from a retracted

relative position into forming position; an automatic means for effecting in sequence in the order named the cycle of operative steps of, first actuating said first pressure operated means to move 5 said heaters from retracted to contactual position, second after a prescribed time interval rendering said first pressure operated means in operation whereby said moving means returns said heaters to retracted position, third actuating said 10 second pressure operated means at the completion of the contactual heating of the plate to relatively move said dies from retracted position into forming position; means for rendering said second pressure operated means inoperative; and 15 means for relatively moving said dies from forming to retracted position.

15. The combination defined in claim 14 and in addition thereto; a non-interference means for preventing initiation of said third operative step 20 before completion of said second operative step.

16. The combination defined in claim 14 in which the operative cycle of said automatic means is manually initiated and said means for actuating said second pressure operated means to relatively 25 retract said dies is manually operated.

17. The combination defined in claim 14 in which said first and second fluid pressure operated means are controlled by first and second electric circuit means respectively; and in addition thereto, a third electric circuit means for heating said heaters; and a manual gang switch for opening said first and third circuit means.

18. The combination defined in claim 14 in which said second fluid pressure operated means 35 is controlled by a first electric circuit means and said time interval is controlled by a condenser charging second electric circuit means having a normally closed resistance cutout shunt circuit; and in addition thereto, a gang switch for opening 40 both said electric circuit means.

19. In a machine for forming plates of metal at relatively high and critical forming temperatures, a combination of: a pair of dies for simultaneously engaging from opposite sides and forming a plate held between them; a pair of heaters on opposite sides of the plate; resilient means 45 for normally holding said plates in a retracted position, said heaters being arranged adjacent the axis of said dies; a first fluid pressure operated means for moving said heaters from said retracted normal position into heating position with relation to the plate; a first valve means having a first and second position for operating said first fluid pressure operated means, said first position effecting movement of said first pressure operated means to move said heaters into heating position, said resilient means returning said heaters to said retracted position when said valve means is in said second position; a second fluid pressure operated means for relatively moving said dies from a relatively retracted position into a forming position; a second valve means having a first and second position for operating said second pressure operated means the first position of said second valve means causing said second pressure operated means to move said dies into forming position; means for returning said dies to said retractive position when said second valve means is in said second position; a first solenoid for 55 moving said first valve means to said first position; a second solenoid for moving said first valve means to said second position; a third solenoid for moving said second valve means to said first position; a fourth solenoid for moving said second valve means to said second position; an elec-

60 65 70 75

tric power circuit; a master switch for said electric power circuit; a heater shunt circuit connecting said heaters in parallel to said power circuit; a control shunt circuit; a manual switch in said control shunt circuit; a first control relay in said control shunt circuit; a first-shunt-circuit connected to said first solenoid; a normally open first-shunt-circuit switch; a second-shunt-circuit connected to said second solenoid; a normally closed second-shunt-circuit switch; a third-shunt-circuit connected to said third solenoid; a first, normally closed, third-shunt-circuit switch; a second, normally open, third-shunt-circuit switch; a fourth shunt circuit connected to said fourth solenoid; a normally closed, fourth-shunt-circuit switch; a rectifier tube having a filament connected across said electric power circuit and an anode and a cathode connected in parallel with said control relay; a gas trigger electronic tube having a grid, an anode and a cathode; a voltage accumulator circuit between said rectifier cathode and said gas trigger tube grid; a second control relay circuit connected between said rectifier cathode and said gas trigger tube anode, said gas trigger tube cathode being connected to place said second control relay in parallel with said first control relay; a voltage discharge circuit for discharging said voltage accumulator circuit; a normally closed switch in said discharge circuit; a normally closed switch in said first control relay circuit, said first control relay when energized closing said first-shunt-circuit switch, opening said second-shunt-circuit switch and opening said discharge circuit switch, and said second control relay when energized opening said first control relay circuit switch, closing said second third-shunt-circuit switch and opening said fourth-shunt-circuit switch, and one of said heaters opening said first third-shunt-circuit switch when moved from retracted position.

20. The combination defined in claim 19 and in addition thereto; a resistance shunt circuit for said voltage accumulator circuit; a normally closed switch in said voltage accumulator circuit in parallel with said resistance shunt circuit; a normally closed switch means for opening said first and second shunt circuit means; and a manual gang control for opening said last mentioned switch and switch means.

21. The combination defined in claim 19 and in addition thereto; a potentiometer connected in said voltage accumulator circuit for adjusting the time rate of voltage increase in said circuit.

22. The combination defined in claim 19 and in addition thereto; a normally open switch means for closing said heater shunt circuit, a relay for closing said switch means and a relay circuit for energizing said relay, connected across said power circuit; a first selective switch for closing said relay circuit in a first position and opening said relay circuit in a second position; a second selective switch in said third shunt circuit for either closing said third shunt circuit in a first position or for short-circuiting said voltage accumulator circuit in a second position; a third selective switch for connecting said first shunt circuit switch to said first solenoid in a first position or to said third solenoid in a second position; a fourth selective switch for connecting said second shunt circuit switch to said second solenoid in a first position or to said fourth solenoid in a second position; and a manual gang selective means for placing all of said four selective switches either in their first positions or in their second positions.

23. In a machine for localized forming of plates

and other objects of metals and other materials at relatively high and critical forming temperatures, including means for forming the plates and other objects while at said temperatures, the combination of: means for holding the plate; a first heating body independent of said forming means and arranged on one side of the held plate, said heating body having a heating surface facing toward and conforming to the juxtaposed local plate portion to be formed and normally held with said heating surface in spaced relation with said plate portion in position to radiantly heat said plate portion; a second heating body independent of said forming means and arranged on the other side of the held plate, said second body having a heating surface facing toward and conforming to the juxtaposed local plate portion to be formed and normally held with said heating surface in spaced relation with said plate portion in position to radiantly heat said plate portion; and automatic means for sequentially, first simultaneously moving said heating bodies into contact with the two sides of said plate respectively, then after a brief predetermined interval retracting said heating bodies to their normal position preparatory to the operation of said forming means.

24. The combination defined in claim 14, and in addition thereto: manual means for rendering inoperative said second fluid pressure operated means and lengthening said time interval.

25. In a machine for forming plates and other objects of metals and other like materials, at relatively high and critical forming temperatures, the combination of: means for holding the plate; a movable body having means for heating the body and normally held in spaced relation with the plate for radiant heating thereof; a forming means movable into and out of forming engagement with the plate; means for moving said body into and out of contact with the plate for heating the plate by thermal conduction, said heating means being effective on said body in either spaced or contact position thereof; and means including means made operative by movement of the body out of engagement for subsequently moving said forming means into forming engagement with the plate.

26. In a machine for a localized forming of plates of metals or other materials at relatively high or critical forming temperatures the combination of: means for holding the plate; a body; means for heating the body; means for moving the body into and out of engagement with the plate at the locus desired to be formed; said body locally heating the plate by thermal conduction when in engagement therewith; means additional to and separate from said body for forming the plate while the plate at said locus is at a temperature caused by said conductive heating, and means for moving said forming means into forming engagement with said heated locus, said means including means made operative by the movement of said body out of engagement with said plate so that said forming means is moved into forming engagement with the locus while the temperature of the same is at the critical forming temperature.

27. A machine for forming plates and other like objects of metals and other material comprising means for heating a plate; a heating element slidably mounted for movement into and out of engagement with said plate; means for normally holding said element out of engagement with said plate; means for moving said element into en-

gagement with said plate to heat an area thereof; forming means movable into and out of forming engagement with the heated area of said plate; means for rendering said moving means operative to move said element into engagement with said plate against the action of said holding means; means for timing said engagement whereby said moving means is rendered inoperative after a predetermined lapse of time, whereby said holding means returns and holds said element out 10

5 of engagement with said plate; means for moving said forming means into forming engagement with said plate; and means including means actuated by movement of said element out of engagement with said sheet for rendering the means operative for moving said forming means into forming engagement with the heated area of the plate.
